(57) **CLAIM**

The ornamental design for an optical instrument, as shown and described.

DESCRIPTION

FIG. 1 is a front perspective view of an optical instrument according to the invention.

FIG. 2 is a left side elevational view of the instrument.

FIG. 3 is a right side elevational view of the instrument.

FIG. 4 is a rear elevational view of the instrument.

FIG. 5 is a front elevational view of the instrument.

FIG. 6 is a top plan view of the instrument; and,

FIG. 7 is a bottom plan view of the instrument.

In the above drawings, any portions shown in broken lines do not form a part of the invention.
